UNITED STATES PATENT OFFICE.

FREDERIC C. MORTON, OF NEW HAVEN, CONNECTICUT, ASSIGNOR OF ONE-HALF TO
FRED BURTON CARLISLE, OF CRANSTON, RHODE ISLAND

TIRE-BUILDING MACHINE.

1,298,767.

Specification of Letters Patent.

Patented Apr. 1, 1919.

Application filed May 31, 1913, Serial No. 770,873. Renewed August 2, 1918. Serial No. 248,071.

To all whom it may concern:

Be it known that I, FREDERIC C. MORTON, a citizen of the United States, residing in New Haven, in the county of New Haven and 5 State of Connecticut, have invented an Improvement in Tire-Building Machines, of which the following description, in connection with the accompanying drawings, is a specification, like letters on the drawings 10 representing like parts.

The present invention relates to a tire building machine, and is embodied in an improved arrangement for smoothing down and shaping the successive layers of fabric 15 on a rotatable shaping core after the fabric has been stretched and laid upon the peripheral surface of said core.

One purpose of the invention is to arrange the apparatus so that the complex movement 20 of the shaping device which is employed, as said device moves over and shapes the fabric on the core, will be fully automatic and synchronous with the rotary movement of the core, so that the spinning in operation is entirely independent of the judgment of the operative, and absolutely uniform throughout the process of building up the carcass.

A further feature of the invention relates to novel means for producing the necessary 25 movement of the smoothing and shaping devices with relation to the core, and, as far as relates to this feature of the invention, it is immaterial whether the operation is fully automatic or not.

35 In accordance with the invention, the smoothing and shaping device, which will be hereinafter termed a spinning roll, is mounted on a support which is automatically movable in a direction substantially parallel to 40 the axis of the core so that the periphery of the spinning roll follows and remains in contact with the curved surface of the core; while the spinning roll itself is movable on the said support in a direction parallel to its 45 own axis, so that the peripheral part or edge of the roll gradually changes its position with relation to the surface of the fabric during the rotation of the core.

It is desirable, though not essential, that 50 two rolls should be employed, so that the layer of fabric at both sides of the longitudinal median line thereof can be smoothed down and pressed into conformity with the core at a single operation; and, for purposes 55 of illustration, the apparatus is shown as

provided with two rolls which act simultaneously. There is, however, no essential co-operation between the rolls, and either roll can be used independently.

In the construction shown to illustrate the 60 invention, the rolls are mounted on movable supports having guideways on a supplemental frame which is movable or adjustable with relation to the core.

Figure 1 is a plan view of an apparatus 65 embodying the invention; and Fig. 2 is a similar view of the same showing the parts in the position reached at, or approximately at, the end of the wiping-in operation.

Referring to Fig. 1, the rotating core 1 is 70 shown as mounted on a shaft 2 adapted to be driven in any suitable or usual way, as by a belt on a pulley 3; and the said core is shown as having laid thereon one layer of fabric 4. The rolls are carried on a swinging frame 5 which is shown as pivotally connected at 6 with a part of the main frame of the machine, and adapted to be locked in the operative position shown by means of a locking pin 7. The rolls themselves are indicated as thin disks 8 having rounded edges adapted to engage the outer surface of the fabric 4, and each roll is rotatable upon an axle 9 along which the hub of the roll is longitudinally movable. These axles 9 are connected with supports 10 which are capable of movement toward the axis of the core 1, the said supports being mounted on guides 12 forming part of a supplemental frame 13 which is adjustable on the swinging frame 5 90 for the purpose of adapting the device for use with cores of different sizes. In the construction shown, the main part of the supplemental frame 13 is provided with slots 14 engaged by nuts 15 secured on bolts 16 which are stationary with relation to the swinging frame 5, so that the said frame 13 can be moved toward or from the core 1 and locked in the position desired.

Each support is adapted to be yieldingly drawn along its guide, springs 17 being herein shown as constituting the means for bringing about this result. The supports are further shown as provided with handles 18 whereby the action of the springs can be manually supplemented, if necessary.

The supports are further shown as provided with a suitable locking device for holding them separated when the apparatus is not in use, the supplemental frame 13 be- 110

ing shown as provided with a pivoted lever 19 having an actuating handle 20, the said lever being connected by means of links 21 with the two supports 10, the axis of the lever being between and in line with the points of connection with the supports, so that when the lever is turned into line with the guides 12, the two supports will be held at their point of widest separation. One 10 of the links 21 is shown as provided with a lost motion connection with one of the supports, as indicated at 22, so as to leave the rolls 8 free to come into equal contact with the fabric on the core 1 under 15 the action of the springs 17.

As shown in Fig. 1, the frame 5 is swung into position for operation, and the locking lever 19 has been moved from its locking position, so that the two rolls 8 are firmly 20 pressed into engagement with the fabric through the action of the springs 17. In order to produce the lengthwise movement of the rolls 8 toward the axis of the core 1 when the core begins to rotate, the rotary 25 movement of the rolls, which is caused by peripheral contact with the fabric on the core is utilized to move the said rolls with relation to the supports 10. As herein shown, each of the rolls 8 is provided with a 30 gear 23, shown as forming a part of the hub of the roll, said gear 23 meshing with a gear 24, which is secured on a screw threaded stem 25. This screw threaded stem co-operates with a female thread formed in a nut 26 35 which extends laterally into a cylindrical guide 27 forming part of the support 10, this guide fitting and surrounding the screw threaded stem 25. It is obvious that the entire guide might be screw threaded, if desired: the purpose, however, of using the nut 26 being to provide means for readily 40 restoring the parts to their normal condition after the operation has been finished, the nut 26 being shown as mounted on a stem 28 45 having a handle 29, so that the said nut can be moved in a guide-way 30 out of engagement with the threads on the stem 25, so that the rolls 8 can be pushed back without 50 engaging the threads in the return movement.

A spring 31 is shown as interposed between the nut 26 and the guide 30 for the purpose of holding the said nut in position during the operation. The rotation of the 55 roll 8 will turn the screw threaded stem 25, so that the said stem, the gear carried thereby, and the roll co-operating with said gear, will be moved with relation to the frame from the position shown in Fig. 1, toward 60 the position shown in Fig. 2, and during this movement, the supports 10 will be moved laterally toward the core 1 and toward each other; if both sides are operated upon at once, so that the rolls will be held 65 closely in contact with the fabric through-

out, spinning in the fabric, at the same time having a tendency to push the same toward the axis of the core, so that an effectual shaping or stretching action is obtained.

The final position of the rolls can be positively determined by means of adjustable stops 32 which are shown as bolts threaded in the supports and held by lock nuts 33, the said stops being adapted to come into engagement with the sides of the supplemental frame 13 after the supports have been moved to the limit desired.

In Fig. 2 the nut 26 is shown as withdrawn from engagement with the threaded stem 25, although, in actual operation, this 80 nut will not usually be withdrawn until the locking lever 19 has been moved to locking position, and the parts are ready to be restored to their normal position. An adjustable stop 34 is also shown as located on the 85 face of the support 10 to engage the gear 24 and limit the return movement of the wiper rolls and determine the normal position thereof.

While the actual movement of the rolls in 90 completing the shaping of the fabric, is, in all cases, a resultant of a movement along the axis of the rolls and a movement generally transverse thereto, the general direction of the movement depends upon which part 95 of the fabric the rolls engage first; and the actual direction of travel of the rolls along their axes is immaterial, so far as relates to the invention, so long as such direction of travel is approximately tangential to the 100 curvature of the core throughout its shaping portion.

What I claim is:

1. In a tire building machine, a rotatable core adapted to receive a strip of fabric, combined with a roll yieldingly held in contact with the fabric on the core; means for rotating the core; and means whereby the rotation of the core is caused to produce a movement of the said roll in a direction 110 toward the axis of the core.

2. In a tire building machine, a rotatable core, combined with rolls at opposite sides thereof; supports for said rolls; means for moving said rolls transversely with relation 115 to said core, to carry said rolls into contact with the opposite sides thereof; and means whereby the rotation of said rolls, due to contact with said core, produces a movement of said rolls toward the axis of the core.

3. The combination with a rotatable core to receive a strip of fabric; of a rotary spinning-in device movable on its own axis, and adapted to engage the surface of the fabric on the core; means for automatically moving said spinning-in device toward the core; and means for automatically causing a gradual movement of said spinning-in device on its own axis toward the axis of the core.

4. The combination with a rotatable core

adapted to receive a strip of fabric; of a support movable in a direction parallel to the axis of the core; a spinning-in device consisting of a disk rotatably mounted in said support; and means for moving said spinning-in device with relation to said support in the direction of its own axis.

5. The combination with a rotatable core adapted to receive a strip of tire-fabric; of a spinning-in device consisting of a wheel or disk having a screw-threaded stem; a support for said spinning-in device having a guide for said stem and a screw-thread in said guide to coöperate with said stem; and means for yieldingly pressing said support toward said core.

10. The combination with a rotatable core

adapted to receive a strip of tire-fabric; of a disk having a screw-threaded stem; a support for said disk having a guide for 20 said stem and a screw-thread in said guide to coöperate with said stem; means for yieldingly pressing said support toward said core; and means for disengaging the screw-thread in the guide from the screw-threaded 25 stem.

In testimony whereof I have signed my name to this specification in the presence of two subscribing witnesses.

FREDERIC C. MORTON.
